P. R. FORMAN

DOOR SHOE CONSTRUCTION

Filed Dec. 9, 1922

Inventor
Paris R. Forman
By his Attorney S. Darby & Darby

UNITED STATES PATENT OFFICE.

PARIS R. FORMAN, OF RAHWAY, NEW JERSEY, ASSIGNEE TO NATIONAL PNEUMATIC COMPANY, OF NEW YORK, N. Y., A CORPORATION OF WEST VIRGINIA.

DOOR-SHOE CONSTRUCTION.

Application filed December 9, 1922. Serial No. 606,009.

To all whom it may concern:

Be it known that I, PARIS R. FORMAN, a citizen of the United States, residing at Rahway, county of Union, and State of New Jersey, have made a certain new and useful Invention in Door-Shoe Constructions, of which the following is a specification.

This invention relates to door shoe constructions and more particularly to such 10 type of door shoe constructions as is employed in the street railway art where the door shoe is carried at the front edge of the door so that if in closing the door encounters an obstruction the door shoe comes in 15 contact with the obstruction and as a result thereof controls the door motor to accomplish one of a number of operations.

It is the general practice to employ the 20 collapsing of the door shoe, or, to be more exact, the contacting of the door shoe with an obstruction to control an electric circuit which in turn controls the door motor whereby, upon actuation, the door motor is reversed to cause the door to move towards 25 the door open position and thereby allow the obstruction to be removed.

The particular object of the invention is to provide a door shoe construction which is simple in structure, efficient in operation 30 and economical in manufacture.

A further and more specific object of the invention is to provide a door shoe which renders the safety feature or control effective throughout the entire length thereof.

35 A further object of the invention is to provide a construction of mounting for the lower edge of the door shoe which renders the lower edge thereof as sensitive as any other portion throughout the length thereof.

40 Further objects of the invention will appear more fully hereinafter.

The invention consists substantially in the construction, combination, location and relative arrangement of parts, all as will be 45 more fully hereinafter set forth as shown by the accompanying drawing and finally pointed out in the appended claims.

Referring to the drawing:

Figure 1 is a view in elevation partly dia- 50 grammatic and partly broken away show-

ing a door with a door shoe construction of my invention applied thereto.

Fig. 2 is an enlarged detail view partly in section and partly broken away of the lower end of the door showing the support 55 of the door shoe.

Fig. 3 is a similar view showing the upper end of the door shoe and the support means therefor.

The same part is designated by the same 60 reference character wherever it occurs throughout the several views.

It is customary in the street car art to employ at the front edge of the door, such as a sliding door 1, what is generally designated 65 as a shoe and which is illustrated at 2. The shoe consists, in this instance, of a coil of wire 3 extending substantially the height 70 of the door. This coil of wire is connected by means of a conductor 4 to a shoe 5 which travels with the door, which shoe 5 travels on a conducting track 6. Extending through the center of the coil of wire 3 and normally out of contact therewith is a wire 7 which wire is connected by the wire 8 with 75 a shoe 9 carried by the door which shoe travels over the conducting track 10. The wires 3 and 7 are covered generally with rubber, canvas or other material 2, and it will be apparent that if the shoe comes in 80 contact with an obstruction during the closing movement of the door, the wires 3 and 7, as a result thereof, will be placed in contact with each other, thereby establishing 85 circuit connection between the conducting tracks 10 and 6, the establishment of which circuit is utilized in a manner well understood in the art to effect the safety control of the door operating motor, which features form no part of my present invention. 90

The top of the shoe 2 is supported by a bracket 15 which is suitably secured to the front edge of the door 1 (see Fig. 3), and the insulating bushing 16 is employed for supporting the end of the wire 7, the said bushing likewise being supported by the bracket 15. In door shoe structures of this nature it will readily be apparent that a support for the lower edge of the shoe of similar construction to that illustrated for the top of 95 100

the shoe, would render the intermediate point of the shoe sensitive upon meeting an obstruction, but would render the lower edge thereof incapable of operation upon encountering an obstruction. Inasmuch as the foot or heel of a passenger passing through the door is apt to become caught during the closing movement of the door, it is extremely desirable that the shoe structure be sensitive 10 substantially throughout its height and especially at the bottom thereof, and my present invention is directed to supplying an efficient means for effecting a sensitive control of the bottom portion of the shoe.

15 In the form shown I provide a bracket 20 pivotally mounted at one end to the front edge of the door at a point between the top and bottom thereof, the free edge of the bracket forming a support and attachment for the lower end of the shoe 2, the middle wire 7 being insulated from the coil 3 by means of a suitable insulating bushing 16, as hereinbefore described.

Secured to the pivoted arm 20 and preferably by a pivotal connection 21, is an arm 25 of insulating material provided with a conducting portion 22. When the shoe is in its fully extended position the parts are in the position shown in Figs. 1 and 2. When, 30 however, the lower portion of the shoe comes in contact with an obstruction, the lower portion of the shoe structure is moved around the pivot 23 of the arm or bracket 20 so that the conducting portion 22 of the 35 lever or arm carried thereby is moved so as to establish the circuit connection between the conducting fingers 24 and 25 which contact fingers are electrically connected to the conducting wires 4 and 8, as above illustrated.

40 It will readily be apparent from the foregoing that I have thus provided means for ensuring a proper completion of the circuit between the contact rails 6 and 10, irrespective of where the shoe encounters an 45 obstruction up to the approximate top of the door itself, and that the means provided are not in substitution to the normal control effected by the wires of the shoe itself, but are in addition thereto, whereby either 50 or both become effective.

The shoe may be maintained in its normal extended position by any one of a number of means which will readily suggest themselves to those skilled in the art. By the arrangement in Fig. 2 I show one exceedingly simple arrangement wherein a spring 27 is employed which serves for this purpose.

Many modifications and changes in details will readily occur to those skilled in the art without departing from the spirit and scope of my invention as defined in the claims, but having now set forth the objects and nature of my invention, and having shown and described a construction embodying the principles thereof, what I claim as

new and useful and of my own invention, and desire to secure by Letters Patent is:

1. In a safety shoe contact device for power operated doors, the combination with an electric circuit, of means carried by the 70 front edge of said door for controlling said circuit, and means for controlling said circuit upon movement of said first mentioned means independently of the control thereof by said first mentioned means.

2. In a safety shoe contact device for power operated doors, the combination with an electric circuit, of means carried by the 75 front edge of said door for controlling said circuit, comprising a suspended coil spring and a wire located longitudinally therein, 80 said wire and spring comprising terminals of said circuit, and means for controlling said circuit independently of said wire and spring upon movement thereof bodily relative to said door.

3. In a safety shoe contact device for power operated doors, the combination with an electric circuit, of means carried by the 85 front edge of said door for controlling said circuit, comprising a suspended coil spring and a wire located longitudinally therein, 90 said wire and spring comprising terminals of said circuit, a movable support for the lower end of said spring and wire, and means for controlling said circuit by the 95 movement of said support.

4. In a safety shoe contact device for power operated doors, the combination with an electric circuit, of means carried by the 100 front edge of said door for controlling said circuit, comprising a suspended coil spring and a wire located longitudinally therein, 105 said wire and spring comprising terminals of said circuit, a support for the lower end of said spring and wire, mounted upon for movement relative to said door, and means for controlling said circuit by the movement of said support.

5. In a safety shoe contact device for power operated doors, the combination with an electric circuit, of means carried by the 110 front edge of said door for controlling said circuit, comprising a suspended coil spring and a wire located longitudinally therein, 115 said wire and spring comprising terminals of said circuit, a support for the lower end of said spring and wire, mounted upon for movement relative to said door, an arm carried by said support, and terminals for said circuit controlled by said arm whereby said circuit is closed when said arm is moved towards said door.

6. In a safety shoe contact device for power operated doors, the combination with an electric circuit, of means carried by the 120 front edge of said door for controlling said circuit, comprising a suspended coil spring and a wire located longitudinally therein, 125 said wire and spring comprising terminals 130

of said circuit, a support for the lower end of said spring and wire, mounted upon for movement relative to said door, an arm carried by said support, terminals for said circuit controlled by said arm whereby said circuit is closed when said arm is moved towards said door, and means for normally

maintaining said arm and support extended from said door.

In testimony whereof I have hereunto set my hand on this fifth day of December A. D., 1922.

PARIS R. FORMAN.
